UNITED STATES PATENT OFFICE.

WILLIAM H. GOLDING, OF CHELSEA, MASSACHUSETTS.

CLAMP.

SPECIFICATION forming part of Letters Patent No. 310,195, dated January 6, 1885.

Application filed June 7, 1884. (No model.)

To all whom it may concern:

Be it known that I, WILLIAM H. GOLDING, a citizen of the United States, residing at Chelsea, in the county of Suffolk and State of Massachusetts, have invented certain new and useful Improvements in Clamps, of which the following is a specification, reference being had therein to the accompanying drawings.

This invention relates to a clamp or press, and the object in view is to provide an instrument, press, clamp, or tool for compressing and holding certain materials in desired positions while certain work is performed thereon, and which at the same time will be capable of presenting said materials in different positions, so that work may be carried on or effected at different points or different parts of the material.

So far as holding the work is concerned, the tool, implement, or device is a clamp, and, being provided with means for compressing the material clamped, it may also be denominated a "press." It is capable of use as a compressing - clamp in assembling the parts of articles—such as boxes made of wood, metal, or other material—when said parts are to be joined together by means of nails, glue, solder, or other connecting means or devices; and it is also capable of use in the process of manufacturing tablets or pads of bill-heads, letter-heads, memorandums, blanks, &c., and can also be advantageously used in clamping any material to be made into any article which comprises several parts which are to be united, and I therefore do not limit my invention to its use in any particular art, but it comprehends any and all uses of the clamp constructed as hereinafter more particularly described, and embodying the novel features hereinafter specifically claimed.

Referring to the drawings, Figure 1 is a plan of my clamp open and sustaining work. Fig. 2 is a plan of the same closed and sustaining work. Fig. 3 is an end elevation. Like letters indicate like parts in all the figures.

A represents the end casting, which, by means of the horizontal flanges A', perforated, as shown, for the passage of screws or bolts, may be secured upon any suitable bench or table. Each of the standards A is bifurcated, and each of the bifurcations is ar-

ranged at a right angle to the other, and is provided with inwardly - projecting flanges, A², on which rest the bottom boards, B, which are held in place by screws passing through the flanges A² into the under surface of each of the bottom boards. A space, C, is left between the lower edges of the bottom boards, and extends from end to end of the foundation or frame, for a purpose hereinafter mentioned. One of the bifurcations of each of the standards is provided with a bearing, D, for the rod D', passing from end to end of the foundation or frame, and forming, in connection with a similar rod, D², a portion of the clamp proper, the remaining portions of said clamp consisting of two cross - bars, E E'. Each of the cross-bars is provided with an integrally-projecting arm, F, adapted to come in contact (when the clamp is swung to an open position) with stops G on the bifurcation of the standard which is provided with the bearing D, the object of the said arm and stop being to maintain the clamp proper in a substantially-horizontal position when open.

At the middle of the cross-bars E E' is a bearing, E², one for the clamping - screw H, provided with a crank or handle, H', outside of the arm, and with a rotatably - mounted bearing-block, H², at the inner end. In the opposite cross - bar is a bearing - block, H³, which may be cast integrally with the arm; or, as shown in this case, provided with the spindle H⁴, mounted in the bearing E² of the arm, which is also provided with a thumb or set-screw, H⁵. The spindle H⁴ is reduced in size to form a shoulder, H⁶, to bear against the inner face of the cross-bar E', so that when the thumb-screw is loosened the spindle of the bearing - block H³ may be rotated in the bearing E². By this construction one or both of the bearing-blocks may be rotated.

In the cross-bar E is an adjusting-screw, I, and upon the standard A is a step, I', against which the end of the adjusting-screw rests. By means of the adjusting-screw I the clamping-frame is raised or lowered, so as to bring the bearing-blocks farther from or nearer to the bottom boards. In this manner the frame is adapted to support work of different sizes transversely at the center thereof and centrally therein.

J J represent following-boards, which in

this instance are rectangular and are used to be intercepted between the bearing-blocks and any work held within the clamp to prevent marring the work.

5 The manner of using the clamp and press is as follows: For instance, in the manufacture of boxes a rectangular block of a size equaling the interior dimensions of the box is first laid upon the bottom boards, B. The 10 end boards of the box are then placed, one at each end of the frame, and the two side boards are placed upon the form, so that these parts shall rest within the bottom of the box—that is, cornerwise—as shown in Figs. 2 15 and 3, when the clamp-screw H is revolved, forcing the bearing-blocks either against the ends of the box or against the following-board J, which may be used, if desired, and the parts are firmly bound in their designed 20 relative position, when they may be fastened by any suitable devices. Now, by lifting the frame and turning the work as it is held therein by the pressure of the bearing-blocks, the thumb-screw H³ being raised, the work 25 may be reversed and the frame again dropped, when the remaining sides may be secured to the ends and the work removed. Another instance in using the clamp and press is in binding and otherwise ornamenting cigar- 30 boxes, the boxes being held in the clamping-frame with or without the following-boards while successive edges of the same are covered with the binding, previously provided with paste. The frame is lifted for the 35 successive turning of the box to expose new edges for binding. Another instance of the use of the clamp and press is the formation of bill-heads, letter-heads, blanks, &c., into tablets or blocks, in which case the right-angled disposition of the bottom boards again 40 serves the purpose of arranging the separate sheets or blanks in due regularity with each other, and by means of the following-boards and clamping-screw they are compressed and 45 the frame is opened outwardly, as shown in Fig. 1, when paste or any suitable cement may be applied to the edges of the sheets, and the binding-sheet, if used, placed on the pasted edges, when the frame is again turned over 50 onto the bottom boards, where the work may be allowed to rest in contact therewith to assure the smooth application of the binding-sheet to the edges of the blanks.

In the drawings, Figs. 1 and 2, K represents the work held between the following-boards, as described.

It is apparent that each of the bearing-blocks may be mounted on a tightening-screw, and that an adjusting-screw may be provided in 55 each cross-bar of the clamp.

What I claim is—

1. A clamp comprising cross-bars united by tie-rods and provided with bearing-blocks and a tightening-screw and pivotally mounted upon a base having a bed the walls of

which are arranged at right angles to each other, substantially as specified.

2. A clamp comprising cross-bars, each provided with a rotatable bearing-block and a tightening-screw centrally arranged therein 70 and pivoted to a frame or bed having walls arranged at right angles to each other, substantially as specified.

3. A clamp comprising cross-bars having bearing-blocks, a tightening-screw, and tie-rods, one of which forms a pivot for the frame, said cross-bars having projecting arms at their pivoted ends, in combination with a frame or bed having walls arranged at right angles to each other and having stops to limit the movement of the clamping-frame when open, substantially as specified. 75

4. A clamp comprising a frame of cross-bars and connecting tie-rods having bearing-blocks and a tightening-screw, the frame being 80 pivotally connected to a bed provided with a lug arranged to support the clamp by means of an adjusting-screw projecting therefrom, substantially as specified.

5. The frame comprising the bifurcated 90 standards having inwardly-projecting flanges, and the bottom boards or walls secured to said flanges and arranged at a right angle to each other, in combination with a clamp pivoted to said frame, substantially as specified. 95

6. The frame comprising the bifurcated standards having inwardly-projecting flanges, and the bottom boards or walls arranged at a right angle to and at a distance from each other at their lower edges, substantially as 100 specified.

7. The bifurcated standard provided at one side thereof with projecting stops and at the other side thereof with projecting flanges and at the top of one of the bifurcations thereof 105 with a hub or bearing, substantially as shown and described.

8. The clamp-frame consisting of two cross-bars, each having at one end thereof a projecting arm and a bearing for a tie-rod, and each 110 having at the opposite end a similar bearing for a similar tie-rod, and one of the said cross-bars having a bearing for a binding-screw, substantially as shown and described.

9. The combination of the standards A, inclined bottom boards, B, spaced as at C, with the clamping-frame provided with the rotatable bearing-block H³, and the tightening-screw H, provided with the rotatable bearing-block H², substantially as shown and described. 115

10. The combination, with the clamping-frame comprising the bars E E', rods D' D', tightening-screw H, and adjusting-screw I, with the bottom boards, B, and end standards, A, one of which is provided with the lug I', 120 substantially as shown and described.

11. The combination, with the clamping-frame provided with adjusting-screw I, bearing-block H³, set-screw and tightening-screw H, and bearing-block H², of the standard A, 130

having the lug I', substantially as shown and described.

12. A clamp comprising a V-shaped trough, and a frame pivoted thereto and provided with a tightening-screw, substantially as specified.

13. A clamp comprising a V-shaped trough, and a frame pivoted thereto and provided with

a tightening-screw and with an adjusting-screw, substantially as specified.

In testimony whereof I affix my signature in presence of two witnesses.

WILLIAM H. GOLDING.
